UNITED STATES PATENT OFFICE.

PHILIP W. MOORE, OF EVANSTON, ILLINOIS, ASSIGNOR TO THE P & M COMPANY, OF CHICAGO, ILLINOIS, A CORPORATION OF ILLINOIS.

ANTICREEPER.

1,170,926.

Specification of Letters Patent.

Patented Feb. 8, 1916.

Application filed December 30, 1914. Serial No. 879,712.

To all whom it may concern:

Be it known that I, PHILIP W. MOORE, a citizen of the United States, residing at Evanston, in the county of Cook and State of Illinois, have invented certain new and useful Improvements in Anticreepers, of which the following is a specification.

My invention relates to an anti-creeper, that is, to a device for preventing the longitudinal creep of a railroad rail, and particularly to a type of device comprising two elements, one having a jaw engaging one edge of the rail base, and the other a similar jaw engaging the opposite edge of the rail base, each of such elements having a hook or jaw which extends around and has a wedging engagement with a part of the other element. The advantage of an anti-creeper of this type is that the movable element, that is, the one standing away from the tie, may be driven into an intimate wedging engagement with the other element so as to produce a very firm, reliable and permanent hold on the rail.

One of the principal objects of my present invention is to provide an anti-creeper of this general type which will be lighter, more compact and less cumbersome than the device of the sort heretofore put on the market, without, however, sacrificing strength or holding power.

A further object is to provide in an anti-creeper of this type, a form of engagement between the two elements which, because of the contour of the interlocking parts, will minimize the chance of one of the parts backing away or being shaken loose from the other by vibration of the rail or other like disturbing influences.

The invention has for further objects such other new and improved constructions, arrangements and devices relating to anti-creepers as will be hereinafter described and claimed.

The invention is illustrated, in a preferred embodiment, in the accompanying drawings wherein—

Figure 1 is a side elevation of the device shown as applied to a rail, a portion of the latter being illustrated in section. Fig. 2 is a sectional plan taken on line 2—2 of Fig. 1. Fig. 3 is a sectional view, on line 3—3 of Fig. 2, and Figs. 4 and 5 are views, in perspective, of the two elements or members of which the device is composed.

Like characters of reference designate

like parts in the several figures of the drawings.

Referring to the drawings, A represents a rail, the base flange of which is designated 60 B, and C one of the ties on which the rail is laid.

The anti-creeper, in the preferred embodiment shown, consists of two interlocking elements D and E, the former adapted to 65 bear against the tie C and the latter being driven toward the tie as far as it will go in applying the device to the rail. The element D consists preferably of a substantially triangular base 10 having an opening 70 11 cut therein for the sake of lightness; a jaw 12 adapted to engage one edge of the base flange B of rail A, a tie abutting flange 13 and a hook 14 which is connected with the triangular base 10 by means of angularly disposed webs 15 and 16, the tie abutting flange 13 being a projection from and a part of the web 16. A web 17 intervenes between the web 15 and the tie abutting flange 13. 80

The movable element E is similarly formed. It has a triangular base portion 18, a jaw 19, adapted to engage the opposite edge of the base flange B from that engaged by jaw 12, and a hook 20 connected 85 to the main body of the anchor by angularly disposed webs 21, 22 between which is a cross strut 23. The element D has a tapered or wedge formed rib 24, preferably a continuation of the base 10, which is engaged 90 by hook 20, the interior surface of the hook being shaped accordingly. The element E is formed with a similar wedging rib 25 engaged by the hook 14. 95

The device is applied to the rail by placing the element D on the rail base with its tie abutting flange 13 against tie C, hooking the movable element over the other edge of the rail base and driving it toward the tie as far as it will go. This produces a 100 wedging engagement between the pairs of wedges and hooks 24, 20 and 25, 14, which draws the rail engaging jaws 12, 19 together, producing a powerful clamping action on the rail. The movable member may 105 be driven by striking it with a hammer, first on one end and then on the other. In this way there is no danger of twisting or skewing the parts of the device on the rail. In most anti-creeping devices of the wedge 110 type the driven element can be reached by the hammer at one end only so that a twist-

ing or skewing of one part or the other is likely to result when the free or movable member is driven toward the tie which, unless it is observed and corrected by striking 5 the other member, lessens or destroys the effectiveness of the hold of the device on the rail.

It will be seen that the parts of the device are constructed so that they will be 10 both light and strong. All needless metal is dispensed with. This is an important factor in the practical success of an article of this sort, put out in large numbers, because of the saving effected both in manufacturing cost and in transportation.

I claim:

1. An anti-creeper comprising two co-engaging members, one provided with a tie abutting part, and each provided with a rail 20 base engaging jaw formed below the plane of the bottom of the rail base with a laterally outstanding wedge-shaped rib adapted to be engaged by the other element.
2. An anti-creeper comprising two co-engaging members, one provided with a tie abutting part, and each provided with a rail 25 base engaging jaw, formed below the plane of the bottom of the rail base with a laterally outstanding wedge-shaped rib, and with a hook adapted to extend around the rib on the other member.
3. An anti-creeper comprising two co-engaging members, one provided with a tie abutting part, and each formed with a rail 35 base engaging jaw, with a wedging rib projecting outwardly from said jaw, and with a hook adapted to extend around the rib of the other member without embracing the jaw thereof.
4. An anti-creeper comprising two co-engaging members, one provided with a tie abutting part, and each formed with a rail 40 base engaging jaw, with a wedging rib projecting outwardly from said jaw, and on the end opposite the jaw with a hook adapted to extend around the rib of the other member without embracing the jaw thereof.
5. An anti-creeper comprising two members having a wedging engagement with 50 each other at opposite ends of the device, each member being provided with a jaw extending around an edge of the rail base, and one of them with a tie abutting part; one of said wedging engagements being provided by a wedge formed rib projecting laterally 55 from the jaw of one of said members and a hook on the other which engages said rib without embracing the jaw on which the rib is formed.
6. An anti-creeper comprising two co-engaging members each formed with a jaw 60 adapted to fit one edge of the base flange of the rail, a hook at the opposite end adapt-

ed to engage the other member, and with two angularly arranged webs which extend 65 from the corners of said jaw respectively to the diagonally opposite ends of the hook.

7. An anti-creeper comprising two co-engaging members each formed with a jaw adapted to fit one edge of the base flange 70 of the rail, a hook at the opposite end adapted to engage the other member, two angularly arranged webs which extend from the corners of said jaw respectively to the diagonally opposite ends of the hook, and with a 75 cross web in the space between said angularly disposed webs.

8. An anti-creeper comprising two co-engaging members each formed with a jaw adapted to fit one edge of the base flange 80 of the rail, a wedging rib projecting laterally from said jaw, a hook at the opposite end adapted to engage the wedging rib of the other member without embracing the jaw thereof, and with two angularly disposed webs which extend from the corners of the jaw respectively to the diagonally opposite ends of said hook.

9. An anti-creeper comprising two members having a wedging engagement with 90 each other, one adapted to bear against a tie and the other to stand away from the same, one of said members being formed at one extremity below the plane of the bottom of the rail base with a laterally outstanding 95 wedge-shaped rib and the other with a hook which engages said rib.

10. An anti-creeper comprising two members having a wedging engagement with each other, one adapted to bear against a 100 tie and the other to stand away from the same, one of said members provided with a base portion adapted to extend under and in contact with the base flange of the rail and with a jaw adapted to engage one edge of 105 the base flange of the rail, said base portion extending beyond the jaw below the plane of the bottom of the rail base in the form of a wedge-shaped rib; the other of said members being provided with a hook to 110 engage said rib.

11. An anti-creeper comprising two members having a wedging engagement with each other, each consisting of a base portion 115 extending under and in contact with the base flange of the rail, a jaw to engage one edge of said base flange, the base portion extending beyond the jaw below the plane of the bottom of the rail base so as to provide a wedge-shaped outstanding 120 rib, and a hook adapted to engage, in each case, said rib formed on the other member.
